(57) **CLAIM**

The ornamental design for a fixed bearing insert, as shown and described.

DESCRIPTION

FIG. 1 is an upper perspective view of a fixed bearing insert showing my new design;

FIG. 2 is a lower perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a rear view thereof;

FIG. 9 is an upper, environmental perspective view thereof;

FIG. 10 is an upper, environmental perspective view thereof;

FIG. 11 is an environmental, right side view thereof; and,

FIG. 12 is an environmental, front view thereof.

In FIGS. 9-12, the broken lines depict environmental subject matter only and form no part of the claimed design.
